UNITED STATES PATENT OFFICE

CLARENCE W. HANSELL, OF ROCKY POINT, NEW YORK, ASSIGNOR TO RADIO CORPORATION OF AMERICA, A CORPORATION OF DELAWARE

ANTENNA

Application filed January 18, 1927. Serial No. 161,769.

This invention relates to antenna arrangements, and more particularly to short wave antennæ lead-in wires, and a method and means for coupling them to the antenna.

5 In arranging for the radiation of high frequency energy it is frequently found that the length of lead-in from the antenna is considerably greater than a wave length, and that in this lead-in standing waves are set up which cause great losses. In fact, I find that the flow of large quantities of wattless current over even a straight conductor may sometimes create a potential gradient of hundreds of volts per inch, inasmuch as the high frequency makes for high reactance.

10 Another disadvantage of an ordinary lead-in system is its tendency to radiate energy which may be differently directed and out of phase with that radiated by the antenna proper.

15 It is an object of my invention to overcome these difficulties, and to provide a lead-in which will obviate the possibility of standing waves and high losses, and which will not effect appreciable radiation.

20 I accomplish these objects by providing, instead of a simple lead-in or a haphazardly arranged pair of lead-in wires, a pair of lead-in wires so coupled to the antenna that they possess the characteristics of an infinite transmission line.

25 The specification is accompanied by a drawing in which Fig. 1 is a wiring diagram of an arrangement according to my invention;

30 Fig. 2 is a schematic layout, in perspective, of an embodiment of my invention; and

35 Fig. 3 shows an antenna of harmonic length.

40 Certain characteristics of a transmission line which may be demonstrated mathematically I shall more simply illustrate by reference to a supposititious transmission line extending to infinity. Such a transmission line of infinite length would obviously be characterized by a total absence of reflections and

45 standing waves, for the reason that the impressed energy would never reach the end of the line to be reflected, and standing waves usually are caused by a reflected wave combining with the original wave.

If a source of current were connected to such a fictitious transmission line there would be no apparent difference between the consequent effect and that which would be caused by connecting a resistive load to the same source. The energy supplied to the line would be dissipated in it, for such energy could not conceivably reach the end of the line. As in the case of a resistive load, there would be a definite limit to the rate of flow of energy, because the rapidity of energy absorption would depend upon the flow velocity in the line, and this in turn depends, for both a finite and an infinite line, upon the relative inductive and capacitive characteristics of the line, as determined by the physical dimensions and spacing of the conductors composing it.

55 This equivalent resistance or apparent impedance of a transmission line of specified transverse dimensions when supposed of infinite length is termed the characteristic impedance of the line. In the case of two $\frac{1}{4}$ " wires, approximately one foot apart, the characteristic impedance is about 600 ohms.

60 Now suppose that at a finite distance from the beginning of such a fictitious infinite transmission line a break is made. Then, because a finite subtracted from an infinite leaves an infinite, the line extending from the break to infinity would still be an infinite transmission line, and would still have the same characteristic impedance as before. The finite transmission line extending to the break typifies a transmission line in use, and if, across the remote terminals of this finite transmission line, an impedance is connected equal to the characteristic impedance of the infinite transmission line, then the finite transmission line will possess all of the desirable features already attributed to the fictitious line, namely, no reflections and standing waves, substantially unity power factor, and substantially no wattless current losses.

65 Referring to the drawing, the short wave antenna is represented by the numeral 2, and to it there are coupled the conductors 4, which, by way of the blocking condensers 6, are coupled to the output inductance 8 of the 70

75 80 85 90 95 100

transmitter 10. According to my invention the points "A" and "B" are so spaced that the impedance therebetween is equal to the characteristic impedance of the conductors 4, considered as a transmission line.

5 One simple procedure for determining when the proper location of the points A and B has been obtained utilizes a plurality of ammeters inserted along the lead-in wires, which are made to read alike. To avoid the 10 possibility of locating the ammeters symmetrically with respect to a standing wave, at least three ammeters should be used, and these should be spaced unequally. In Fig. 1 15 the ammeters are 22, 24, and 26, and the space between 22 and 24 is different from that between 24 and 26.

Referring now to Fig. 2, the antenna is the conductor 2, and it is supported upon the 20 masts 12 and insulated therefrom by the insulators 14. The conductors 4, as before, are coupled to the antenna at the properly spaced points "A" and "B", and these conductors are guided to the building 16, in 25 which the transmitter is housed. The point of bend of the transmission line 4 may be supported by a wire 18 and insulators 20.

The antenna need not necessarily be one half a wave in length. It is desirable that 30 the coupling points be symmetrically located with respect to a potential node and a current antinode. Thus in Fig. 3 a linear oscillator one and one half waves in length is illustrated. In both Fig. 1 and Fig. 3 the solid 35 curve indicates potential, while the dotted curve indicates current.

The lead-in wires do not effect appreciable 40 radiation because they tend to neutralize one another, and also because they extend in the direction of their wave propagation, instead of transversely thereof.

It is perfectly feasible that the antenna be 45 horizontal, oblique, or vertical, but it is well in the case of a vertical or oblique antenna to increase the elevation in order that the 50 capacitance from each half of the antenna to ground may not be appreciably unbalanced.

What I claim is:

1. In combination, means to radiate high 55 frequency energy including a simple linear oscillator, and a plurality of lead-in wires directly coupled thereto at points so spaced that the external impedance across which the lead-in wires are connected is equal to the characteristic impedance of the lead-in wires.

2. An antenna arrangement for the radiation 60 of very short waves comprising a simple linear oscillator an odd number of half wave lengths long, and lead-in wires directly symmetrically coupled thereto at points so spaced that the impedance therebetween equals the characteristic impedance of the lead-in wires.

3. An arrangement for the radiation of 65 short waves comprising a transmitter having an output circuit, a short wave antenna,

comprising a linear radiator an odd number of half wave lengths long, blocking condensers, and lead-in wires coupled to the output circuit through said blocking condensers, and directly coupled to the linear 70 radiator of the antenna at points so spaced that the external impedance across which the lead-in wires are connected is equal to the characteristic impedance of the lead-in wires.

4. An antenna arrangement for the radiation 75 of very short waves comprising a straight wire oscillator an odd number of half wave lengths long, and lead-in wires directly symmetrically coupled thereto at points so spaced 80 that the impedance of the portion of straight wire of the oscillator therebetween equals the characteristic impedance of the lead-in wires.

5. The method of adjusting the coupling 85 of a transmission line to an antenna so that there will be no reflection of energy from the antenna end of the line back into the line which includes varying the coupling at the antenna end of the line until a plurality 90 of indicating devices, responsive to high frequency currents, placed in the line, and spaced other than a half wave length or a whole multiple thereof apart, read alike.

6. In a high frequency communication system employing lead-in wires coupled to an antenna, the method of coupling the lead-in 95 wires to the antenna which includes placing a plurality of indicating devices, responsive to high frequency currents, in the lead-in wires unequal distances apart the distances taken being other than one-half wave length 100 or a whole multiple thereof, and varying the coupling of the lead-in wires with the antenna until the indicating devices, responsive to high frequency currents, read alike.

7. In a high frequency communication system employing lead-in wires directly coupled 105 to a short wave antenna, the method of locating the antenna coupling points for the lead-in wires which includes placing a plurality 110 of indicating devices, responsive to high frequency currents, in the lead-in wires unequal distances apart, the distances taken being other than one-half wave length or a whole multiple thereof, and varying the coupling points on the antenna until the indicating 115 devices read alike.

8. In a system for transmitting intelligence 120 from one geographically situated point to another by means of propagated electromagnetic wave energy derived from the flow of high frequency undulatory electrical currents operated upon in accordance with the intelligence to be transmitted, the combination of a simple linear oscillator, and, a plurality of lead-in wires directly coupled 125 thereto at points so spaced that the external impedance across which the lead-in wires are connected is equal to the characteristic impedance of the lead-in wires.

9. In a system for transmitting intel- 130

- ligence from one geographically situated point to another by means of propagated electromagnetic wave energy derived from the flow of high frequency undulatory electrical currents operated upon in accordance with the intelligence to be transmitted, the combination of a simple linear oscillator one-half wave length long, and, a plurality of lead-in wires directly coupled thereto at points so spaced that the external impedance across which the lead-in wires are connected is equal to the characteristic impedance of the lead-in wires.
10. In combination, means to radiate high frequency energy including a simple linear oscillator substantially one-half wave length long, and a plurality of lead-in wires directly coupled thereto at points so spaced that the external impedance across which the lead-in wires are connected is equal to the characteristic impedance of the lead-in wires.
